STORAGE FILING BOX

Jerome J. Carroll, Chicago, Ill.

Application October 27, 1938, Serial No. 237,299

8 Claims. (Cl. 229—23)

The invention relates to collapsible boxes and more particularly to boxes formed from heavy sheet material such as, for example, corrugated cardboard or strawboard, adapted principally, for the storage of transfer files.

Transfer or storage boxes of the character referred to necessarily must be sufficiently stiff and durable to withstand rough handling and to support heavy loads. Preferably, they embody means to protect their contents from dirt. At the same time they must be inexpensive and easily collapsed for storage or shipment. Also, they preferably consist of a minimum number of parts to facilitate setting the box up for use and should provide a smooth interior bottom surface to facilitate the packing of papers or the like therein. A smooth exterior surface also is very essential to facilitate efficient stacking.

It is therefore, an object of the invention to provide an improved, inexpensive, strong, rigid and dustproof collapsible filing box.

Another object is to provide a collapsed box of the character described for economical shipment or storage when not in use, and one that can be easily and quickly set up, by inexperienced persons.

The foregoing and such other objects of the invention as will appear hereinafter, will be more readily understood from a perusal of the following specification, in which reference will be made to the accompanying drawing, in which:

Fig. 1 is a perspective view of the improved transfer or storage filing box, showing the top in open position.

Fig. 2 is a transverse sectional view taken on line 2—2 of Fig. 1, showing the box closed in full lines, and open in dotted lines.

Fig. 3 is a longitudinal sectional view taken on line 3—3 of Fig. 1, showing the box closed.

Fig. 4 is a view of one of the blanks.

Fig. 5 is a view of the other blank.

The improved box 11, illustrated in the accompanying drawing, preferably is made from two blanks 12 and 13, best illustrated in Figs. 4 and 5, respectively. Preferably, they are strawboard or corrugated cardboard or other suitable stiff durable sheet material. The blank 12 is substantially rectangular and is suitably scored transversely as at 14, 15, 16 and 17 to define a flap portion 18, an inside bottom portion 19, a rear wall portion 21, a top portion 22 and a tongue portion 23.

The other blank 13 also is substantially rectangular and is suitably scored longitudinally along line 24 and also transversely, along lines 26 and

27 between said score line 24 and the adjacent edge 25. The blank is cut through along lines 28 and 29 in alignment, respectively, with lateral score lines 26 and 27. The edge 25 of the blank 13 has laterally projecting flap portions 31, one 5 outwardly longitudinally of each score line 26 and 27, which portions are partly defined by score lines 32 aligned with the edge 25. Cutting and scoring the blank 13 as above noted, defines two end wall portions 33, a front wall portion 34, an 10 outer bottom portion 35 and end wall bottom flap portions 36.

To complete the collapsed box, the end wall portions 33 are bent, along their respective score lines 26 and 27, to about right angles to the intermediate front wall portion 34. The rear wall portion 21, of blank 12, is positioned with its end edges in abutment with the complementary edges of the end wall portions 33. Adhesive strips 37 then are secured to the outside faces of the rear 20 wall portion 21 and of the end wall portions 33 to join the corners.

To set up the collapsed box for use, as best shown in Figs. 1, 2 and 3, said joined blanks 12 and 13, are bent along their remaining score lines 25 and the inside bottom portion 19 is bent toward and spans the distance from the rear wall portion to the front wall portion 34. The flap portion 18, on said bottom portion 18, is inserted upwardly into a position substantially parallel to and inside the front wall portion 34, thus providing a double thickness front wall having its two thicknesses preferably arranged spaced part. The end wall bottom flap portions 36 then are bent over toward each other beneath the bottom portion 19 35 and the outside bottom portion 35 then is bent rearwardly against the said flaps to position the free longitudinal edge of said outside bottom portion 35 against the bottom of the rear wall portion 21. The free longitudinal margin of the 40 outside bottom portion 35 then is joined securely to the lower margin of the rear wall portion 21 by an adhesive strip 38.

The box now is set up for use and, because of the double bottom and double front wall structure, it is materially strengthened and consequently can withstand heavy loads. The double bottom wall construction also provides a smooth interior bottom surface to facilitate insertion of the papers and a smooth exterior bottom surface which facilitates stacking.

Although the inwardly extending end wall bottom flap portions 36 terminate a substantial distance from each other, as illustrated, it is apparent that they may be of sufficient length to 55

meet. However, from a manufacturing viewpoint, the end wall bottom flap portions will, in most instances, have a length equal to the width of the bottom portion 35 which is complementary to said flap portions as best illustrated in Fig. 5.

Prior to closing the top 22, the end wall top flap portions 31 are bent inwardly toward each other. The top 22 then is bent down along score line 16 over flap portions 31 and the integral tongue 23 is bent and inserted between the inner and outer front wall portions 18 and 34, respectively.

It should be noted that the upper edge of the inner front wall or flap portion 18, is substantially flush with the upper edge of the outer front wall portion 34 so that, when closed, the outside face of the top 22 is elevated from the upper edge of the outer front wall portion, a distance approximating the thickness of the material. This arrangement is desirable to avoid interference with the edge of the outer front wall portion by a box placed thereon in stacking. The top 22 is adequately reinforced by the underlying edge of the inner front wall portion 18 and the underlying end wall top flap portions 31.

If desired, the various edges of the walls and flaps likely to become frayed during use may be suitably protected by reinforcing strips of binding tape 39, or the like, and suitable pliable tabs 41 and 42 may be attached to facilitate removal of the box from a stack and opening of the top 22.

Although the box is shown and described as being constructed of two separate blanks suitably joined by adhesive strips 37, it is apparent that a single blank may be used. In such instance the two blanks illustrated, preferably would be integral along one of the co-incident rear and end wall edges now joined by one of the adhesive strips 37 and only one adhesive strip 37 would be required to join the other co-incident rear and end wall edges. However, the two piece blank is preferred because of lower material cost due to the smaller stock size of the material required to make the blanks.

Although a preferred construction has been illustrated in the accompanying drawing, and specifically described herein, it is not desired that the invention be limited to the precise disclosure but that it embrace such structures as fall within the spirit of the invention and the scope of the appended claims.

I claim:

1. A collapsible box having single rear and end walls, a front wall, a bottom portion joined to the lower edge of the rear wall spanning the distance from the rear wall to the front wall to provide an inner bottom wall, a flap on said bottom wall extending upwardly into the box parallel to and closely adjacent the front wall, bottom flaps on each end wall underlying said inner bottom wall, a bottom portion joined to the lower edge of the front wall spanning the distance from the front wall to the rear wall and underlying the end wall bottom flaps, means for securing the last-named bottom portion in the aforesaid underlying relation upper flaps on the end walls extending inwardly toward each other, a top joined at its rear edge to the upper edge of the rear wall to span the distance from the rear wall to the front wall, and a tongue on the front edge of said top insertible between the front wall and the bottom wall flap adjacent thereto.

2. A collapsible box having single rear and end walls, a front wall, a bottom portion joined to the lower edge of the rear wall spanning the dis-

tance from the rear wall to the front wall to provide an inner bottom wall, a flap on said bottom wall extending upwardly into the box closely adjacent the front wall, bottom flaps on each end wall underlying said inner bottom wall, a bottom portion joined to the lower edge of the front wall spanning the distance from the front wall to the rear wall and underlying the end wall bottom flaps, means for securing the last-named bottom portion in the aforesaid underlying relation upper flaps on the end walls extending inwardly toward each other, and a top joined at its rear edge to the upper edge of the rear wall to span the distance from the rear wall to the front wall.

3. A collapsible box having single rear and end walls, a front wall, a bottom portion joined to the lower edge of the rear wall spanning the distance from the rear wall to the front wall to provide an inner bottom wall, a flap on said bottom wall extending upwardly into the box closely adjacent the front wall, bottom flaps on each end wall underlying the inner bottom wall, a bottom portion joined to the lower edge of the front wall spanning the distance from the front wall to the rear wall and underlying the end wall bottom flaps, an adhesive strip overlapping and joining the co-incident edges of the outside bottom wall and the rear wall, upper flaps on the end walls extending inwardly toward each other, a top joined at its rear edge to the upper edge of the rear wall to span the distance from the rear wall to the front wall, and a tongue on the front edge of said top insertible between the front wall and the bottom wall flap.

4. A collapsible box formed of two blanks joined to constitute an integral structure, said structure comprising, a blank cut and scored to define only the top, rear, inside bottom and inside front wall portions of said box, and a second blank cut and scored to define only the ends, outside front and outside bottom wall portions, and top and bottom end wall flap portions of said box, said joined blanks being constructed and arranged so as to form a box having single rear and end walls, and double front and bottom walls.

5. A collapsible box having single rear and end walls, a front wall, and inner and outer bottom walls, said inner bottom wall being integral with the rear wall, means securing the outer bottom wall in underlying relation with reference to the inner bottom wall, a flap on said inner bottom wall to provide an inner front wall of substantially the same height as and spaced inwardly from the front wall, a top hingedly joined along one edge to the rear wall, a tongue on the free edge of said top insertible between said front walls, and end wall flaps insertible beneath said top, all integral.

6. A collapsible box having single rear and end walls, a front wall, and inner and outer bottom walls integral respectively with said rear and front walls, means securing the outer bottom wall in underlying relation with reference to the inner bottom wall, a flap on the free edge of the inner bottom wall of a width substantially equal to the height of the front wall arranged substantially parallel to but spaced inwardly from said front wall, a top integral with said rear wall, and a tongue on said top insertible between said front wall and said bottom wall flap.

7. A collapsible box having single rear and end walls, a front wall, said front and end walls being integral, adhesive strips joining said end

- walls and said rear wall, an outer bottom wall integral with the front wall, an adhesive strip joining its free edge to the rear wall, an inner bottom wall integral with said rear wall, a flap 5 on the free edge of said inner bottom wall arranged inwardly of and substantially parallel to and adjacent the front wall, a top integral with said rear wall, and a tongue on said top insertible between the front wall and said bottom wall 10 flap.
8. A collapsible box having single rear and end walls, a front wall, said front and end walls being integral, adhesive strips joining said end

walls and said rear wall, an outer bottom wall integral with the front wall, an adhesive strip joining its free edge to the rear wall, an inner bottom wall integral with said rear wall, a flap 5 on the free edge of said inner bottom wall arranged inwardly of and substantially parallel to and adjacent the front wall, a top integral with said rear wall, a tongue on said top insertible between the front wall and said bottom wall flap, and flaps on the end walls insertible beneath said 10 top.
